UNITED STATES PATENT OFFICE

DANA E. HARDING, OF MELROSE, MASSACHUSETTS, ASSIGNOR TO HARDING ENGINEERING COMPANY, OF EAST BOSTON, MASSACHUSETTS, A CORPORATION OF MASSACHUSETTS

MARKING MACHINE

Application filed January 6, 1928. Serial No. 244,880.

My present invention relates to marking machines, and more particularly to an improved drag mechanism for use in connection therewith.

5 In the patent issued to me under No. 1,641,082 and dated August 30, 1927, I have described and claimed an improved marking machine for use in marking various characters, such as the weight or area on flexible material, such as leather, and in the machine therein illustrated, flexible material such as leather is fed through an area measuring machine, and as the measured material passes through the machine, the mechanism 10 by means of which the area is visually indicated is associated with mechanism for setting a plurality of marking wheels to correspond with the area that is visually indicated and such marking wheels are operated 15 to impress on the flexible material the area of the flexible material.

It has been found in the practical application of the above machine that sometimes blurring of the printed characters occurs 20 due primarily to the fact that the flexible material is constantly being fed through the machine and there is an appreciable length of time in which the marking devices are in engagement with the flexible material. The 25 marking devices being stationary, as far as onward movement with respect to the machine is concerned and the leather being movable, the leather is dragged under the marking devices and the characters impressed are 30 smoothed.

In my present invention I have overcome 35 the difficulty above enumerated and have, in carrying out my invention, associated with the marking devices and the frame carrying the same, a resilient brake or drag which is brought into engagement with the movable flexible material, just prior to the engagement of the marking devices therewith and remains in engagement with such flexible material until the marking devices are removed 45 from engagement therewith. The effect of the resilient drag or brake on the flexible material is to maintain it stationary on the support regardless of the drag that may be 50 exercised thereon by the conveying devices

and to maintain such flexible material stationary during the time that the marking device is in engagement therewith. By the use of this device, therefore, I have positively prevented blurring of smooching of the characters impressed on the flexible material by the marking devices. 55

The principal object of my invention, therefore, is an improved marking machine.

Another object of my invention is an improved brake or drag for temporarily maintaining the movable material stationary for a predetermined length of time. 60

Other objects and novel features of the construction and arrangement of parts comprising my invention will appear as the description of the device progresses. 65

In the accompanying drawings illustrating the preferred embodiment of my invention, 70

Fig. 1 is a side elevation;

Fig. 2 is a plan view of one end of Fig. 1, and

Fig. 3 is an enlarged plan view of the character wheels and frame on which the same are mounted, as indicated in Fig. 1. 75

In the accompanying drawings, 10 designates a base or platform over which moves in any approved manner an endless conveyor 11, and forming part of the frame of the machine is a cross bar 12, on which is mounted a laterally extending framework 13. Formed integral with the framework 13 are bearing members 14 in which are rotatably mounted a shaft 15. On the shaft 15 is rotatably mounted a framework 16 which carries at its extreme outer end a plurality of wheels 17 on which are formed characters it is desired to impress on a flexible material 18, such as leather, that is moved along the table or platform 10 by the endless conveyor 16. The wheels 17 are adapted to be rotated independently of each other by mechanism that is indicated by the reference characters 19, 20 and 21 and for a fuller disclosure of 80 this mechanism, reference is hereby made to the Patent No. 1,641,082 above referred to. The function of this mechanism is to set the character bearing wheels 17 in appropriate 85 position to impress on the flexible material 90

18 characters to indicate the area as measured by the area machine to which the same may be applied and which area is also visually indicated at an appropriate part of the machine. 5 The frame 16 rotating about the shaft 15 and carrying the character wheels 17 thereon, it is obvious that when the frame 16 is allowed to rotate that the character wheels 17 will assume the position indicated in dotted lines. 10 Extending up through suitable openings in the platform 10, is a belt 22, such belt acting as a platen for the character wheels 17. Secured to the under side of the frame 16 by screws 23 is a member 24 of resilient material 15 and formed integral with said member 24 and at each end thereof are resilient arms 25 which, as will be obvious from an inspection of Fig. 3, lie on either side of the group of character wheels 17. Normally the position 20 of the member 24 and arms 25 is such that the arms 25 are slightly below the character bearing wheel 17, as will be clearly seen from an inspection of Fig. 1, and when the frame 16 is rotated on this shaft 15, it will be obvious 25 that the arms 25 will move into engagement with the flexible material 18 before the character bearing wheels 17 will engage with such flexible material. Therefore, the engagement of the resilient arms 25 with the flexible ma- 30 terial 18 will cause a gripping action of such flexible material by the arms 25 and the endless conveyor 11 or the upper surface of the platform 10 and in this manner the flexible material 18 will be brought to rest before the 35 character wheels 17 engage therewith, and such flexible material will remain at rest until after the character bearing wheels 17 have been removed therefrom. With this construction, therefore, there is no relative movement between the flexible material 18 and the character bearing wheels 17 at the 40 instant such character bearing wheels 17 are in engagement with the flexible material and blurring or smooching of the characters impressed on the leather is prevented. 45

While I have necessarily shown the preferred embodiment of my invention, somewhat in detail, it is to be understood that I may vary the size, shape, and arrangement 50 of parts without departing from the spirit of the invention.

Having thus described my invention, what I claim as new is:

1. In a device of the kind described, the 55 combination of a pivotally mounted frame, a plurality of character wheels rotatably mounted at the end thereof, a platen, an endless conveyor adapted to move material to be worked on over the platen, means for mov- 60 ing the frame about its pivot to bring the character wheels into engagement with the material being fed over the platen, a resilient member secured to said pivotally mounted frame and adapted to engage with the mov- 65 ing material in advance of the engagement

therewith by the character wheels, and to maintain the material being worked on at rest during the engagement of the character wheels therewith.

2. In a device of the kind described, the combination of a pivotally mounted frame, a platen, character wheels carried by the pivotally mounted frame and adapted to engage with material passing over the platen, means to move the material over the platen and be- 70 tween the platen and character wheels, a resilient member, a pair of resilient arms formed integral therewith and located on either side of the character wheels, said re- 75 sili- 80 lent arms being adapted to engage with the material being worked on in advance of the engagement of the character wheels there- 85 with and to bring the material to rest during engagément thereof by the character wheels.

In testimony whereof, I have signed my name to this specification.

DANA E. HARDING.
